Frederick W. Lawrence
by his attorney,
Edwin H. Brown,

UNITED STATES PATENT OFFICE.

FREDERICK W. LAWRENCE, OF BROOKLYN, NEW YORK.

HOUSE.

SPECIFICATION forming part of Letters Patent No. 288,072, dated November 6, 1883.

Application filed July 2, 1883. (No model.)

To all whom it may concern:

Be it known that I, FREDERICK W. LAWRENCE, of Brooklyn, in Kings county and the State of New York, have invented a new and 5 useful Improvement in Houses and other Buildings, of which the following is a specification.

My improvement involves the use of a skeleton frame, preferably made of tubing, in combination with cement or concrete applied directly to the skeleton frame and filling the 10 spaces between adjacent sections or portions thereof, which form the walls, floors, and other parts of buildings.

In the accompanying drawings, Figure 1 is 15 a vertical section of a building embodying my improvement, and Fig. 2 is a horizontal section of the same.

Similar letters of reference designate corresponding parts in both figures.

20 A designates foot-pieces, consisting of T-shaped iron couplings, with pieces of pipe A' fitted and secured into their sockets a, which are in line.

B designates upright posts or stanchions, 25 which consist of iron pipes screwed into the sockets a' of the couplings A, forming parts of the foot-pieces. One of these posts or stanchions is arranged at each vertical corner of the building, and others may be used between

30 these at such distances apart as will impart to the building the strength which it is desired to have. The foot-pieces and the adjacent parts of the posts or stanchions are embedded in the earth or in a rubble or similar foundation, F. These posts or stanchions are connected by horizontal braces C at suitable distances apart. These braces C consist of iron 35 pipes; but the iron pipes of which these braces are formed may be much smaller than the

40 pipes forming the posts or stanchions B. The posts or stanchions B are made of sections of pipe united by couplings b. The braces C extend between the posts or stanchions, and are fitted into tapped holes or sockets c, with

45 which the pipes forming the posts or stanchions are provided. The pipes forming the braces will be reversely screw-threaded at the ends—namely, will be provided with a right-hand screw-thread and at the other end with

50 a left-hand screw-thread—and the tapped holes or sockets c are correspondingly screw-

threaded, so that the brace-pipes may be simultaneously screwed at both ends into the tapped holes or sockets of opposite posts or stanchions.

The lower braces, C, are shown as embedded in the earth or foundation F, but the upper braces are above the foundation.

The floor of the lower compartment or story of the building may be made by covering the 60 earth with cement, and by laying boards over that, if desirable. Where there are to be windows braces C may be arranged just above and below the positions which the lintels and sills are to occupy, and other braces, C', extend between these braces C, close to the portions which the jambs of the windows are to occupy. Door-frames may be similarly made.

E designates beams or girders extending horizontally between the posts or stanchions B. 70 They are formed of large iron pipes and are united to the posts or stanchions by T-shaped couplings b, which also secure sections of the posts or stanchions together. The pipes forming the beams or girders are reversely screw-threaded at the ends, and the sockets of the couplings b, into which they screw, are correspondingly screw-threaded, so that said pipes may be screwed at both ends simultaneously into the said sockets.

I have shown rods F' as extending obliquely between the upper horizontal braces, C, and the beams or girders E. These may be secured by rivets.

Between the beams or girders E joists G extend. They are made of small iron pipes screwing into tapped holes or sockets in the pipes forming the beams or girders E. They are provided at the ends with reversed screw-threads, so that they may be screwed simultaneously into the pipes forming opposite beams or girders. The tapped holes or sockets into which the pipes forming the joists G are screwed must of course be screw-threaded correspondingly to the ends of the pipes which 90 they are to receive.

Braces H, consisting of small iron pipes screwed into tapped sockets with which the pipes forming the joists are provided, connect the joist-pipes together. The pipes forming these braces H and the sockets in which they fit are reversely screw-threaded, so that these 100

brace-pipes may be screwed simultaneously into the sockets of the opposite joist-pipes, which the brace-pipes connect.

In lieu of employing the brace-pipes H, a set of pipes arranged in a lower plane and connecting opposite beams or girders, E, may be employed. Such lower series of pipes would be reversely screw-threaded at the ends and fitted into correspondingly screw-threaded 10 sockets.

Cement or concrete is set and molded with the aid of boards or otherwise around the skeleton forming the walls and the skeletons forming the floors, and a complete building is thus produced. The cement or concrete is applied directly to the skeleton frame and fills 15 all the spaces between adjacent sections or portions thereof.

In making the walls a boxing is built around 20 the pipes for a certain height and then the cement or concrete is rammed in, the boxing being raised from time to time until the walls are completed. In building the floors a scaffolding is erected at the point where the ceiling 25 is to be formed, and the cement is rammed down upon it from above till the required thickness is obtained.

Partitions may be made like the walls, but with smaller horizontal pipes. The cement 30 or concrete used on the partition skeletons may have sawdust incorporated with it to make it light.

Plaster may be applied to the walls and 35 ceilings without lathing, if desirable, and boards may be applied to the floors.

I thus produce a simple and cheap building 40 of immense strength and stability, and one which is almost absolutely fire-proof. Owing to the immense strength which is due to such a structure, the walls and floors may be made thinner than usual, and hence the inside space will be increased as compared with ordinary 45 structures possessing the same strength.

Any part of the exterior of the building may 50 be faced with bricks, stone, iron, or other building material, if desired, for the purpose of ornamentation.

A sidewalk-light may be constructed like 55 the floors, with the exception that panes or pieces of glass will be incorporated with or into the cement.

The roof may be made like the floors, except that it will preferably be arranged on a slant.

55 An important advantage of this building

is that, owing to the fact that the floors will be water-proof, a lower story may be completed even to plastering, kalsomining, and painting, while an upper story or stories are still in process of erection. Two sets of workmen may thus be employed at the same time, and the building may be much more speedily completed than when built in the ordinary manner.

Some of the pipes which are used in the 60 construction of the building may be used as ventilating shafts or passages, others as water service-pipes, others as waste-pipes, and still others as gas-conduits, if desirable.

In some cases a part or parts only of a building 70 may be made according to my improvement. The pipes used in carrying out my improvement may be connected in other ways than those described.

What I claim as my invention, and desire 75 to secure by Letters Patent, is—

1. A building comprising in its structure a skeleton of iron, and cement or concrete applied directly to the skeleton, and filling 80 the spaces between adjacent portions thereof, substantially as specified.

2. A building comprising in its structure a skeleton of iron pipes, coupled and connected together, and cement or concrete applied directly to said skeleton and filling the spaces 85 between adjacent sections or portions thereof, substantially as specified.

3. In a building, the combination of pipes forming posts or stanchions, pipes forming 90 beams or girders, couplings connecting sections of the pipes forming the posts or stanchions, and securing the pipes forming the beams or girders thereto, and cement or concrete applied directly to the said pipes and filling the spaces between them, substantially 95 as specified.

4. In a building, the combination of pipes forming posts or stanchions, pipes forming beams or girders, couplings securing the pipes forming the posts or stanchions, and the pipes 100 forming the beams or girders together, pipes forming joists, secured to the pipes forming the beams or girders, and cement or concrete applied directly to the said pipes and filling the spaces between them, substantially as 105 specified.

FREDERICK W. LAWRENCE.
